UNITED STATES PATENT OFFICE.

CHARLES W. LINDSAY, OF HOUSTON, TEXAS.

SINGLE-TRIGGER MECHANISM FOR DOUBLE-BARREL GUNS.

1,261,414.

Specification of Letters Patent.

Patented Apr. 2, 1918.

Application filed June 29, 1917. Serial No. 177,706.

To all whom it may concern:

Be it known that I, CHARLES W. LINDSAY, a citizen of the United States, residing at Houston, in the county of Harris and State 5 of Texas, have invented certain new and useful Improvement in Single-Trigger Mechanism for Double-Barrel Guns, of which the following is a specification.

The object of the invention is to provide 10 a single trigger mechanism whereby both barrels of double barrel guns may be fired successively and in the order desired.

Another object of the invention is to provide means for shifting the mechanism and 15 thus changing the order in which the barrels are fired.

A further feature resides in the provision 20 of a means for preventing a premature discharge of the second barrel due to the recoil of the gun succeeding the recoil after the firing of the first barrel.

It is also the object of the invention to provide a single trigger mechanism which is constructed with a minimum number of 25 parts so that it may be easily and cheaply constructed and easily applied to the firing mechanism of the ordinary double barrel gun.

With the above and other objects in view, 30 the invention has particular relation to certain novel features of construction, operation and arrangement of parts, an example of which is given in this specification and illustrated in the accompanying drawings

35 wherein:—

Figure 1 is a perspective view of the interior of the lock of a gun.

Fig. 2 is a perspective view of the sear actuating means, shown in position to fire the 40 left hand barrel first.

Fig. 3 is a perspective view of said means shown in position to fire the right hand barrel first.

Fig. 4 is a perspective view of said means 45 shown in position after the firing of the left hand barrel and before the release of the trigger.

Fig. 5 is a perspective view thereof shown in position after the firing of the left hand 50 barrel and after the release of the trigger.

Fig. 6 is a fragmentary sectional view of the sear actuating means in cocked position.

Referring now more particularly to the 55 drawings wherein like numerals of reference designate similar parts in each of the figures, the numeral 1 designates the frame of

the usual double barrel gun in the sides of which are pivoted the hammer controlling sears 2, 2, provided at their rear ends with corresponding inwardly turned projections 60 3, 3, through which the sears are actuated and released from the corresponding hammers 4, 4, to permit the firing of the respective barrels. The frame of the gun extends rearwardly forming the upper and under 65 plates 5 and 6 to which the gun stock is secured, the latter of said plates also supporting the trigger mechanism. The numeral 7 designates the trigger whose forward end is pivoted to the block 8. This trigger plays 70 through an alined slot in the lower plate 6, the downwardly projecting portion being formed into a finger grip and above the plate 6 the trigger is widened forming a comparatively wide release plate 9 and this part of 75 the trigger is extended rearwardly forming a finger-like extension 10 which plays in the trigger slot in the plate 6. A flexible U-shaped member is provided whose lower arm 11 rests upon the upper surface of the plate 6 80 and has an oblong slot 12 therein and fitted closely against the under side of the plate 6 is a slide 13 which has a rib that projects up through a slot provided in the plate 6 and projects into the slot 12 and a pin 14 passes 85 through said rib and its ends have bearings in said lugs on arm 11 and the slide 13 has a section thereof roughened as at 16 whereby it may be moved back and forth in its slot so as to adjust said U-shaped member with 90 the result hereinafter explained. The other arm 17 of the flexible U-shaped member extends over the release plate 9 of the trigger 95 7 and has the laterally projecting selecting fingers 18, 18, extending in opposite directions and arranged in staggered relation. This arm is formed of flexible material and its free end normally extends over the release plate 9, said plate declining forwardly slightly from said arm as shown in Fig. 3. 100 Secured to and upstanding from the plate 6 is the post 19 whose upper end is formed into the stops 20 and 21 which are curved over, their free ends pointing downwardly and said stops being spaced apart. The arm 17 105 has an upwardly extending finger 22 provided to engage against one of said stops to prevent the firing of the second barrel after the first barrel has been fired, until the trigger is released and again pulled. When the 110 gun is not cocked the finger 22 will be alined in position behind its corresponding stop,

that is behind the stop 20, in case the mechanism is adjusted to fire the left hand barrel first, as shown in Fig. 2, or behind the stop 21 in case the mechanism is adjusted to fire 5 the right hand barrel first, as shown in Fig. 3. Should the gun be now cocked, the rear end of the sears will be depressed, through the influence of the flat spring 2', pressing upwardly against the other end of the sear 10 and one of the projections 3 will engage against the alined finger 18 and will force said finger down closely against the release plate 9 thus bending the arm 17 slightly over the rear end of said plate, as shown in Figs. 15 1 and 2 and carrying the free end of the finger 22 under the corresponding stop. When the trigger is pulled it will operate, through the finger 18, to elevate the rear end of the sear resting against said finger, releasing the 20 opposite end of said sear from the corresponding hammer and the corresponding barrel will be fired. The movement of the trigger will be arrested by the finger 22 coming in contact with its alined stop 20 or 21, 25 as the case may be, thus preventing the firing of the other barrel. When the trigger is released, the rear end of the sear will be held elevated by the cam face 4' of the hammer, which depresses the opposite end of the 30 sear and the pressure of the plate 9 against the arm 17 will be relieved and said arm will straighten out and assume its original position, carrying the free end of the finger 22 back out of alinement with said stop. When 35 the trigger is again pulled, the finger 22 will pass behind said stop permitting a further elevation of the release plate 9 which will then contact with the projection 3 of the other sear and elevate the same, causing the firing of the other barrel. It will be observed that the fingers 18 are arranged in staggered relation so that when one of them is alined under the corresponding sear projection 3, the other will be alined to 40 miss the corresponding projection of the other sear so as to permit the release plate itself to engage therewith. As shown in Figs. 1, 2, 4 and 5, the mechanism is arranged to fire the left hand barrel first. 45 When in this position when the gun is cocked, the projection 3 will press downwardly against the left hand finger 18, forcing the same closely against the release plate 9 thus causing a curvature of the arm 17 50 and carrying the finger 22 under the stop 20. The other finger 18 will be alined behind the projection 3 of the other sear so as to miss the same. A pull on the trigger will now operate to lift the left hand finger 18, 55 and the rear end of the corresponding sear, disengaging said sear from its hammer and causing a firing of the left hand barrel. The elevation of the release plate 9 is limited by the contact of the finger 22 with the stop 20. 60 Upon releasing the trigger the arm 17 as-

sumes its normal position, as above explained, carrying the finger 22 behind the stop 20 and a further pull on the trigger will permit the release plate 9 to come in contact with the projection 3 of the other sear and fire 70 the other barrel. When in this position the U-shaped member 17 will be held against adjustment by means of the shoulder 23, carried by the plate 6 and which rests in the notch 24 of said member. In case it is desired to fire the right hand barrel first, the U-shaped member may be forced forwardly by the manual manipulation of the slide 13 until the shoulder 23 rests in the notch 25. The right hand finger 18 will then be carried 80 under the corresponding projection 3 and the left hand finger will be carried past the other projection 3 so as to miss the same. Successive pulls on the trigger will then operate as hereinbefore explained to fire first 85 the right hand, then the left hand barrel. The shoulder 23 has sloping sides so that the slide 13 may be moved in either direction and will readily release itself from said shoulder. 90

Upon the firing of the barrel there is first a recoil and then a rebound; this latter movement carrying the trigger into involuntary contact with the finger of the operator which is liable to cause a premature discharge of 95 the second barrel. For the purpose of preventing this premature discharge, I have provided an oblong safety weight 26 having the downwardly extending neck 27 pivoted on the pin 28. This member is normally 100 held in forward position by means of a light spring 29. Upon the rebound, the safety weight, by reason of its inertia, falls backward overcomimg the influence of the spring 29 and the lower end of the neck has an extension 30 which is thereby carried into engagement with the rear end of the extension 10 of the trigger thus temporarily locking said trigger against the involuntary pull of the operator caused by the rebound of the 110 gun. The trigger will be held locked until the period of time, during which there is an involuntary pull on the trigger, has passed and the safety weight will then be swung forwardly by the spring 29, releasing the 115 trigger, and a succeeding pull will cause the firing of the second barrel. 120

What I claim is:

1. A device of the character described including hammer controlling sears, a trigger formed into a common sear-actuating means, a flexible selective sear-actuating means, a stop, a locking member carried by said selective means and normally out of alinement with the stop, said selective means being arranged to be flexed by one of the sears when the corresponding hammer is in cocked position to bring said member into alinement with said stop whereby the trigger is locked against further movement after the first dis- 125 130

charge, said member being automatically released from the stop upon release of the trigger, to permit the further movement of the trigger whereby the common sear-actuating means is brought into engagement with, and actuates, the other sear.

2. A device of the character described including hammer controlling sears, a trigger formed into a common sear-actuating means, a selective sear-actuating means arranged to be actuated by the trigger and adjustable to actuate either sear, a stop, a locking member carried by the selective means and normally out of alinement with the stop, said selective means being arranged to be flexed by one of the sears when the corresponding hammer is in cocked position to bring said member into alinement with said stop whereby the trigger is locked against further movement after the first discharge, said member being automatically released from the stop upon release of the trigger, to permit the further movement of the trigger whereby the common sear-actuating means is brought into engagement with, and actuates, the other sear.

3. A trigger mechanism for double barrel guns including hammer controlling sears, a trigger formed into a common sear-actuating means, a flexible selective sear-actuating means capable of adjustment to actuate said sears alternatively, a stop, a locking member carried by said selective means and normally out of engaging position with the stop, said selective means being arranged to be flexed by one of the sears when the corresponding hammer is in cocked position to bring said member into engaging position with said stop when the trigger is pulled, whereby the trigger is locked against further movement after the first discharge, said member being automatically released from the stop upon release of the trigger to permit the further movement of the trigger whereby the common sear-actuating means is brought into engagement with and actuates the other sear.

4. A trigger mechanism for double barrel guns including hammer controlling sears, a trigger formed into a common sear-actuating means, a flexible selective sear-actuating means capable of adjustment to be brought into actuating position relative to said sears alternatively, locking members one fixed relative to the sears and the other carried by and movable with the selective means said last mentioned member being actuated by one of the sears when the corresponding hammer is in cocked position, into engaging position with the other locking member and locking the trigger against further movement after the first discharge,

said movable locking member automatically disengaging from the fixed locking member upon release of the trigger to permit the further movement of the trigger whereby the common sear-actuating means is brought into engagement with and actuates the other sear.

5. A trigger mechanism for double barrel guns including hammer controlling sears, a trigger formed into a common sear-actuating means, a flexible selective sear-actuating means capable of adjustment to actuate said sears alternatively, a pair of stops, a locking member carried by said selective means and normally out of engaging position with said stops, said selective means being arranged to be flexed by one of the sears when the corresponding hammer is in cocked position to bring said member into engaging position with the corresponding stop whereby the trigger is locked against further movement after the first discharge, said member being automatically released from said stop upon release of the trigger to permit a further movement of the trigger whereby the common sear-actuating means is brought into engagement with and actuates the other sear.

6. A device of the character described including hammer controlling sears, a trigger formed into a common sear-actuating means, a flexible selective sear actuating means, means for adjusting the selective means into operative connection with said sears alternatively, a pair of stops, a locking member carried by said selective means and provided to engage with said stops alternatively accordingly as said selective means is adjusted into operative connection with one or the other of said sears, said member being normally out of operative connection with its corresponding stop and the selective means being arranged to be influenced by one of the sears when the corresponding hammer is in cocked position to bring said member into position to be engaged with the corresponding stop whereby the trigger is locked against further movement after the first discharge, said member being automatically released from the stop upon release of the trigger to permit the further movement of the trigger whereby the common sear-actuating means is brought into engagement with and actuates the other sear.

In testimony whereof I have signed my name to this specification in the presence of two subscribing witnesses.

CHARLES W. LINDSAY.
